MACHINE FOR APPLYING PRESSURE TO
SHOE BOTTOMSSidney J. Finn, Beverly, Mass., assignor to United
Shoe Machinery Corporation, Paterson, N. J., a
corporation of New Jersey

Application April 7, 1937, Serial No. 135,512

36 Claims. (Cl. 12—33)

This invention relates to machines for applying pressure to shoe bottoms and is herein illustrated as embodied in a cement sole attaching machine of the type disclosed in Letters Patent of the United States No. 2,047,185, granted July 14, 1936, upon an application filed in the name of Milton H. Ballard et al.

The machine of the patent mentioned is provided with a plurality of pads for receiving soles and shoes, these pads being arranged to be presented successively at an operating station. Associated with each pad are sole and shoe positioning members or gages for relatively locating the soles and shoes on the pad, these sole and shoe gages being moved yieldingly toward a sole on the pad and the sole gages, after finding and contacting with the edge face of the sole, becoming locked automatically to hold in position the shoe gages which will properly locate the shoe with respect to the sole when the shoe is placed thereon. Pressure is then applied to the shoe to press the sole and shoe against the pad, the pressure being provided by fluid pressure operated mechanism which forces the sole and shoe downwardly some distance into the pad when the full pressure has been applied. It will be seen that if the gages remain in locked engagement with the sole and shoe as these members sink into the pad there may be danger of some of the gages scarring the upper of the shoe as it moves downwardly past the gages or danger of the gages indenting the shoe during the remainder of the pressure applying operation.

It is an object of the present invention to prevent any damage to the shoe by the sole and shoe positioning gages during the pressure applying operation.

With this end in view, a feature of the invention consists in the provision of improved means for releasing or unlocking the sole and shoe gages during the application of pressure to the sole and shoe and for withdrawing these gages from operative engagement with the sole and shoe. As herein illustrated, the gage releasing and withdrawing means is fluid-pressure-controlled and is connected with the same source of fluid pressure supply as the fluid pressure operated mechanism for applying pressure to the shoe. The releasing and withdrawing means is preferably arranged to operate after sufficient pressure has been applied to the sole and shoe by the building up of a predetermined pressure in the pressure system of the machine to clamp the sole and shoe on the pad and thereby to insure against relative displacement of the sole and shoe after the gages have

been withdrawn but before the full pressure has been applied.

The gage releasing and withdrawing means, as herein illustrated, includes a fluid-pressure-operated plunger constructed and arranged through a pivoted member to actuate gage operating and controlling mechanism associated with each pad and thereby to release and positively withdraw or retract all the gages simultaneously to their outer or inoperative positions. In order that this action may not occur until after a predetermined pressure has been applied to the sole and shoe, the plunger is arranged to operate against a spring the resistance of which may be varied as desired for operating, for example, on men's, women's or children's shoes.

In accordance with another feature of the invention means is provided for latching the gages on each pad box in their withdrawn or inoperative positions until the pressure applying operation has been completed, thereby insuring against the return of the gages into engagement with the sole and shoe before the latter have been removed from the pad. As illustrated, the latching means is adapted to operate automatically when the gages have been moved into their outermost or retracted positions. Further means, operated by return of the pressure applying mechanism of the machine to inoperative position, is provided for releasing the latch just before the pad with which it is associated re-enters the operating station at the completion of the pressure applying operation. This latch releasing means is also arranged to maintain the latch in an inoperative position until the gages have positioned another sole and shoe on the pad and the pressure applying mechanism has been moved into operative position. At this time the latch is permitted to return to an operative position so that when a predetermined pressure has been applied to the sole and shoe on the pad, and the gages are released and withdrawn by the mechanism above referred to, the latch will act automatically to lock the gages in their withdrawn positions.

Although the latch is released automatically before the pad is fully located in the operating station, so that the gages are then under the control of their actuating mechanism, the construction and arrangement is such that the usual gage retracting mechanism with which the machine is provided comes into play to prevent the gages from moving inwardly toward the sole and shoe even though the gages are not locked in their withdrawn positions.

With the above and other objects and features in view, including novel details of construction and arrangement of parts, the invention will now be described in connection with the accompanying drawings and will thereafter be pointed out in the claims.

In the drawings,

Fig. 1 is a front elevation of the portion of the machine embodying the present invention;

Fig. 2 is a side elevation of a portion of the machine including one of the pad boxes and pressure applying mechanism associated therewith, and including also portions of the fluid pressure controlling mechanism;

Fig. 3 is a plan view of the forepart of one of the pad boxes illustrating the sole and shoe positioning gage mechanism;

Fig. 4 is a fragmentary plan view similar to Fig. 3 with the gage mechanism withdrawn from operative position;

Fig. 5 is a detail sectional view of the mounting of a latch for locking the gages in the withdrawn position shown in Fig. 4;

Fig. 6 is a front elevation of the mechanism for controlling the operation of the gages and fluid pressure operated means for withdrawing the gages and locking them in inoperative position;

Fig. 7 is a plan view of a portion of the gage withdrawing mechanism shown in Fig. 6;

Fig. 8 is a side elevation of a portion of the mechanism of Fig. 6, as viewed from the left-hand side of that figure; and

Fig. 9 is a side elevation, partly broken away and in section, of a part of the mechanism shown in Fig. 6, as viewed from the right-hand side of that figure.

The mechanism of the present invention for releasing and withdrawing the sole and shoe positioning gages is illustrated herein as embodied in a machine of the type disclosed in the Ballard et al. patent referred to above, the drawings and description being limited to those portions of the machine which are directly concerned with the invention. For a more complete description of the portions of the machine not illustrated or described herein, reference may be had to the patent mentioned.

The cement sole attaching or laying machine comprises a base or column 10 upon which is mounted for rotation about a vertical axis a turret 12 which carries a plurality of pad boxes 14 arranged to be presented in succession at an operating station located at the front of the machine. Each pad box 14 is provided with a yielding pad 16 adapted to receive a sole A and a shoe B (Figs. 2 and 3). The sole A is positioned on the pad by an operator and it is held in position thereon by sole and shoe positioning mechanism best illustrated in Figs. 3 and 4, this mechanism functioning also to locate the shoe relatively to the sole.

The sole and shoe positioning mechanism comprises gage arms 18 for operating on the sole and shoe in the vicinity of the ball line and gage arms 20 for engaging the sole and shoe approximately at the tip line, the gage arms 20 being arranged in crossed relation to each other, as shown in Fig. 3. The gage arms 18 carry at their forward ends sole gages 22 and shoe gages 24, the latter being adjustable relatively to the sole gages by eccentric adjusting mechanisms provided with handles 26. The gage arms 20 for the tip line are likewise provided with sole gages 28 and shoe gages 30 which are relatively adjust-

able by means of handles 32. The gage arms 18 are pivoted by horizontal pins 34 to carrier members 36 which, in turn, are pivoted on substantially vertical pins 38 carried in a frame member 40 secured to the pad box. The tip line 5 gage arms 20 are pivoted on horizontal pins 42 mounted on separate carrier members 43 also pivoted on the vertical pins 38, and these gage arms and the ball line gage arms 18 are freely movable about their respective pivots so that the 10 sole gages on the ends of the arms rest by gravity on the pad 16. Both pairs of gage arms 18 and 20 are normally urged in a direction to move the gages toward each other and toward a sole and shoe on the pad by springs 44, 44 and 46, 46, the 15 springs 44 acting upon the ball line gage arms 18 and the springs 46 acting upon the tip line gage arms 20.

As shown in Fig. 3, the carrier members 36 and 43 are provided with relatively thin overlapping 20 portions 47 in which are formed arcuate slots 48 struck from the centers 38 and through which extends a locking bolt 50. As fully described in the Ballard et al. patent, the locking bolt is arranged to be drawn downwardly into clamping 25 relation with the overlapping portions of the carrier members 36, 43 by mechanism not fully disclosed herein but including a lever 52 (Fig. 3) and a rocker member 54 to lock the gage arms in operative position after the sole gages have contacted with the edge face of the sole on the pad. In this way the position of the shoe relatively to the sole is determined by the locked shoe gages 24, 30 carried by the arms 18 and 20.

The gage arms 18 and 20 are moved about their vertical pivots to withdraw the gages carried thereby from engagement with the sole and shoe and to move them into their outer or inoperative positions by swinging movement of the rocker member 54 toward the left, as viewed in Fig. 3, 40 this rocker member, as described in the patent referred to, carrying projections 56 each arranged to engage a roll on a gage arm and to move the gages into their inoperative position 45 simultaneously. Movement of the rocker member 54 in the direction indicated to withdraw the gages operates first, however, to release the locking bolt 50 and thereafter to move the gages into their withdrawn positions against the action of 50 their operating springs.

The rocker member 54 is actuated by a substantially horizontal link 58 held in this position by a stationary guide member 60 provided with a slot which engages a pin 62 mounted in the right-hand end of the link, as viewed in Fig. 3. The 55 pin 62 carries a roll 64 which rides in a slot 66 formed in an upright arm 68 of a bell crank lever pivoted to the turret on a shaft 72 and having a lower, substantially horizontal arm 70 (Figs. 1 and 6). Movement of the bell crank lever 68 in a counterclockwise direction, as viewed in Figs. 1 and 6, actuates the rocker member 54 to release the locking bolt 50 and move the gage arms 18 and 20 against their springs in a direction to withdraw the gages from the shoe and sole, and movement of the bell crank lever in the opposite or clockwise direction permits the gages to move inwardly toward a sole on the pad under the action of their springs 44, 46. A spring 74, connected between the arm 68 and a pin 76 on the turret, tends normally to swing the bell crank lever in a clockwise direction into a position where the gages will be contacting with a sole on the pad, the movement of the bell crank lever 70 75

being limited by a stop screw 78 arranged to engage the turret 12.

The mechanism with which the machine is provided at the operating station for actuating the bell crank lever 68 and thereby operating the sole and shoe positioning gages comprises a stationary cam 80 fastened to the upper end of a standard 82 and provided with an inclined surface 84 arranged to engage a roll 86 carried by a shouldered screw 87 extending through the horizontal arm 70 of the bell crank lever 68. As each pad box moves into the operating station from left to right, as viewed in Fig. 1, the lever 68 associated with that pad box is, in the machine of the patent referred to, swung in a counterclockwise direction by the cam 80 to release the gage locking bolt and withdraw the gages to inoperative position through the operation of the rocker member 54. When the pad box comes to a stop at the operating station the roll 86 would ordinarily be resting on a ledge member 88 (Figs. 1 and 6) forming a continuation of the stationary cam 80, this ledge member being carried by a lever 90 pivoted at 92 on the stationary cam 80.

In the machine disclosed in the patent mentioned, when it is desired to swing the bell crank lever 68 of the pad box at the operating station in clockwise direction (as viewed in Figs. 1 and 6) and thereby operate the rocker member 54 to permit the gages to be moved inwardly by their springs into contact with the edge face of the sole, the lever 90 and the ledge member 88 carried thereby are moved downwardly by a treadle 94 (Fig. 1) connected to the lever 90 at 95 by a treadle rod 96 working against a treadle elevating spring 98. As the parts are shown in Fig. 6, the ledge member 88 has been moved downwardly by depression of the treadle 94 but, because of other mechanism which forms a part of the present invention, the bell crank lever 68 has not been swung in a clockwise direction by the spring 74 to bring the stop screw 78 against the turret and, accordingly, the sole and shoe positioning gages are still maintained in their withdrawn or retracted positions.

In the machine of the patent referred to, after the sole gages have been permitted to come into engagement with a sole on the pad in the manner described, it is necessary to retain the lever 90 and the ledge member 88 in a lowered position so that the gages will remain locked against the sole. For this purpose a latch 100 is provided, the latch being pivoted on a pin 102 mounted in the stationary cam 80 and being adapted to snap over a shoulder on the lever 90 under the action of a spring 104 connected to the lever 90 at 105 and tending constantly to urge the latch in a counterclockwise direction about its pivot 102. After the sole and shoe have been properly positioned on the pad 16 and have been pressed against the pad by the pressure applying mechanism, the turret rotating mechanism of the machine is operated to cause the pad box and the gage actuating mechanism associated therewith to move out of the operating station. When this occurs a roll 106 on the center 72 rides along an inclined cam surface 107 on the lever 90 and engages an upward projection 108 on the latch 100. This disconnects the latch 70 from the lever 90 and the latter is permitted to return gradually to its original elevated position by the inclination of the cam surface 107. As stated above, the mechanism just described is provided in the machine of the Ballard et al. 75 patent and is fully disclosed therein.

The machine of the patent mentioned is also provided with hydraulically operated pressure applying mechanism for pressing the shoe B against the sole A after they have been properly positioned relatively to each other on the pad by 5 the gage mechanism, the shoe and sole, of course, having been previously treated with cement whereby the sole is to become attached either temporarily or permanently to the shoe bottom. Before proceeding to describe the mechanism of 10 the present invention for automatically withdrawing and latching the sole and shoe gages in inoperative position, a brief description of the hydraulic or fluid pressure operated mechanism for pressing the sole and shoe against the pad 15 will be given.

Each pad box on the turret is provided with pressure applying mechanism comprising a cylinder 110 (Fig. 2) having mounted therein a piston 112 carrying at its upper end a pivoted 20 lever 114 the opposite ends of which are disposed under levers 116 pivoted at 118 to a swinging frame member 120, the latter being secured by a set screw 121 to a shaft 122 rotatably mounted in the turret. The swinging frame member 120 25 is arranged for swinging movement from a rearwardly inclined inoperative position into a substantially vertical operative position over the pad box by a handle 124. One of the two pivoted levers 116 carries a block 126 for engaging the 30 top of a last in the shoe on the pad and the other lever 116 carries a toe rest 128 for engaging the toe portion of the shoe. Upward movement of the piston 112 due to the introduction of fluid such as oil under pressure into the cylinder 35 through a pipe 130, causes the levers 116 to be swung in a direction to bring the abutments 126, 128 into engagement, respectively, with the last and shoe so that the sole and shoe will be forced downwardly against the pad. It will be seen 40 from the foregoing that, if the sole and shoe gages carried by the gage arms 18 and 20 remain in locked position against the sole and shoe as the latter are moved downwardly against the pad, some of the gages may contact with the 45 shoe in such a manner as to mar or otherwise injure the shoe upper. It is desirable, therefore, after the gages have operated to position the sole and shoe relatively to each other on the pad, and the pressure applying mechanism has been ac- 50 tuated sufficiently to clamp the sole and shoe against the pad so that they will be held thereafter in proper relative positions, that the locked gages should be released and withdrawn from engagement with the sole and shoe and maintained 55 in their withdrawn positions for the remainder of the pressure applying operation, this action preferably taking place after a predetermined pressure of, for example, fifty pounds to the square inch has been built up in the fluid pressure system 60 of the machine so that sufficient pressure will have been applied to the sole and shoe to clamp these members against the pad and thereby prevent any relative displacement thereof. The mechanism for accomplishing this result, which 65 forms the subject-matter of the present invention, will now be described.

As indicated above, the bell crank lever 68 in the present construction, has not been swung in a clockwise direction, as viewed in Fig. 6, until 70 the stop 78 is against the turret 12, even though the ledge member 88 is illustrated as having been lowered by the depression of the treadle 94 and, consequently, the gages are not contacting with the sole and shoe. The bell crank lever 68 is held 75

- in the position shown in Fig. 6 by a latch 132 loosely pivoted on the upright arm 68 of the bell crank lever about midway of its length on a screw 134. In order that the latch 132 will always be free on the screw 134, it is actually pivoted on a cylindrical projection 136 (Fig. 5) formed on a clamping nut 138, the nut fastening the screw in the arm 68 but permitting the latch 132 to pivot freely about its cylindrical portion.
- 10 Secured by a screw 140 (Figs. 1 and 8) to the under side of the turret 12 is a stationary angle plate 142 having an inwardly projecting portion arranged to be engaged by a notch in the lower edge of the latch 132. The angle plate 142 may 15 be adjusted lengthwise of the pad box about the screw 140 and maintained in adjusted position by a stop screw 144 (Figs. 6 and 8), the inner end of which engages a portion of the turret 12. The latch 132 is caused to hook over the plate 142 by 20 swinging movement of the bell crank lever 68 in a counterclockwise direction after the sole and shoe have been properly positioned on the pad and a predetermined pressure has been applied thereto. The latch remains hooked over the plate 25 to hold the bell crank lever in the position shown in Fig. 6 and the gages withdrawn during the rotation of the turret for the greater part of one revolution or just prior to the return of the pad box under consideration to the operating station 30 at which time the latch is automatically released, in a manner to be hereinafter described, so that the gages will not be locked in their withdrawn position. The gages will not, however, be moved inwardly toward the sole and shoe by their springs 35 at this time because the release of the latch 132 occurs at such a point in the cycle of the machine that the roll 86 on the horizontal arm 70 of the bell crank lever will have engaged the inclined surface 84 on the stationary cam 80 to retain the bell crank lever in substantially the same position it occupied when latched, although the latch 40 is then raised up away from the plate 142 and is held in such position.
- Before proceeding to describe the fluid pressure 45 operated mechanism of the invention for swinging the bell crank lever 68 in a counterclockwise direction, as viewed in Fig. 6, to withdraw the gages and for permitting the latch 132 to hook over the plate 142 to lock the gages in this withdrawn position, a description will be given of the mechanism for automatically releasing the latch 132 just before the pad box enters the operating 50 station and for maintaining the latch in an inoperative position until the sole and shoe have been relatively positioned on the pad and a predetermined pressure has been applied thereto.
- The swinging frame member 120 (Fig. 2) is 55 swung forwardly into operative position over the pad by the operator, as stated, but is caused to return to a rearwardly inclined inoperative position automatically as the pad box with which it is associated is about to enter the operating station. The mechanism for effecting the automatic movement of the swinging frame 120 into its inoperative position, as disclosed in the Ballard et al. patent, comprises a segmental member 146 (Figs. 2 and 9) loosely mounted on the rotatable shaft 122 which forms the pivot for the swinging frame 120, the member 146 engaging a spring 148 projecting from a lug 150 on the lower portion of the swinging frame. Movement of the segmental member 146 in a clockwise direction against the spring 148 causes the swinging frame to swing rearwardly into its inoperative position, this position being determined by a stop block 152 on

the cylinder 110 which is engaged by a collar 154 fastened by a set screw 156 to a sliding rod 158 arranged to slide through the block 152 and pivotally connected at its forward end by a pin 160 to the swinging frame. The operative or vertical 5 position of the swinging frame 120 is determined by a fiber collar 162 secured by lock nuts 164 on the inner end of the sliding rod 158. Since the swinging frame is fixed to the shaft 122 the latter, of course, turns in its bearings as the swinging frame moves into and out of operative position.

The segmental member 146 is caused to rotate in a clockwise direction by a roll 166 (Figs. 1, 6 and 9) arranged to engage the inclined surface 15 84 of the stationary cam 80 as the pad box moves into the operating station, this roll being carried by a member 168 pivoted to the turret on a pin 170 and pivotally connected to the segmental member 146 by a pin 172. As the roll 166 rides 20 up the inclined surface of the cam 80 the member 168 is swung about its pivot 170 to elevate the pin 172 and to force the segmental member against the spring 148 mounted in the projection or lug 150, thereby automatically returning the 25 swinging frame member to its rearwardly inclined inoperative position.

The opposite end of the shaft 122 has secured to it by a set screw 174 a forwardly extending arm 176 (Figs. 6 and 8) having adjustably secured thereto by slot and screw connections 178 an extension piece 180 the upper edge face of which is curved in a manner to engage a relatively long flat surface on the lower edge face of the latch 132 and to raise this latch upwardly about its pivot 35 134 away from engagement with the fixed plate 142. As the swinging frame 120 is swung into its rearwardly inclined position by operation of the mechanism just described, the shaft 122 turns to elevate the arm 176, 180 and cause it to raise 40 the end of the latch away from the plate 142, thereby releasing the bell crank lever 68 so that it can be swung about its pivot 72 in a clockwise direction, as viewed in Fig. 6, by the spring 74 to permit the sole and shoe position gages to move 45 inwardly under their operating springs into engagement with the sole A on the pad. Since the swinging frame member 120 is swung automatically into this inoperative position as the pad box associated therewith is entering the operating 50 station, the latch will be maintained in an elevated position at that time by the member 180 and the roll 86 on the arm 70 will engage the cam surface 84 on the stationary cam and come to rest on the ledge member 88. Subsequent depression of the treadle 94 lowers the ledge member 88 and permits the arm 68 of the bell crank lever to swing to the right, as viewed in Figs. 1 and 6, thereby permitting the sole gages to move yielding- 55 ingly into engagement with the sole on the pad 60 and to become locked in such position. After the shoe has been positioned on the sole and a part of the sole attaching pressure has been applied, the bell crank lever 68 is caused to swing automatically in a counterclockwise direction, by 65 mechanism next to be described, so that the latch 132 will hook over the fixed plate 142 and lock the gages in their open or withdrawn position, the member 180 having been lowered by turning of the shaft 122 when the swinging frame member 70 was moved into its vertical position by the operator to apply pressure to the sole and shoe and thus permitting the elongated flat surface on the latch 132 to ride on the upper edge face of the 75 plate 142. Accordingly, further movement of the

latch toward the left, as viewed in Fig. 6, by the mechanism now to be described, will cause the latch to hook over the plate 142 and lock the gages in their withdrawn position, this mechanism being best illustrated in Figs. 2, 6 and 9.

The machine is provided adjacent to the operating station with a stationary post 182 (Fig. 2) to which is secured a bracket 184. Secured to this bracket by screws 186 is an upstanding member 188 having an upper portion 190 in the form of a substantially horizontal cylinder having a bore of substantial diameter therein. Mounted for sliding movement in the bore in the cylinder 190 is a plunger 192 having a slot 194 extending lengthwise thereof and through which a pin 196 passes, the pin serving to limit lengthwise sliding movement of the plunger in the cylinder. A pipe 198 is threaded into the lower side of the cylinder in an opening which communicates with the bore therein. The pipe 198 extends downwardly and is connected at its lower end (Fig. 1) to the hydraulic pressure power system of the machine. This fluid pressure system, as fully described in the Ballard et al. patent, is provided with a series of valves through the operation of which in a particular manner, by mechanism not disclosed herein, the free circulation of fluid such as oil through the pressure system is stopped. For the purpose of the present disclosure it is sufficient to state that this free circulation of oil through the pressure system is stopped by the depression of a treadle 200 (Fig. 1) which lowers a rod 202 having a collar 204 (Fig. 2) thereon and between which and a washer 206 is a compression spring 208. The washer 206 rests on the forked forward end of a lever 210 pivoted at 212 and having an inner arm 213 connected at its inner end by a link 214 to an arm 216 forming a part of a pressure inducing valve 218 which is provided on the machine for controlling the fluid pressure system. When the pressure inducing valve 218 is open the oil circulates freely through the system and when the valve is closed fluid pressure is built up in the system and in the pipe 130 to elevate the piston 112 and apply pressure to the sole and shoe, the fluid passing through a three-way valve mechanism 220 (Fig. 1) before entering the cylinder 110. The amount of pressure which may be built up in the system may be as high as 300 pounds per square inch if such a pressure is necessary or desirable in attaching a sole to a shoe bottom. The valve 218 is normally held closed by a spring 222 and depression of the treadle 200 raises the arm 216 to open the valve and cause the fluid pressure mechanism to operate.

Returning now to the gage withdrawing mechanism, illustrated in Fig. 9, the cylinder 190 has extending upwardly therefrom a pair of arms 224 (Figs. 7 and 9) in which is rotatably mounted a pin 226 having secured thereto by a set screw 228 a member 230. The member 230 has a downwardly projecting lug 232 located opposite the forward end of the plunger 192 and a screw 234 is threaded through the lug so that its inner end contacts with the plunger. The screw 234 is held against the plunger 192 by a tension spring 236 extending through an opening 237 in the member 230 and connected thereto by a pin 238, the spring being connected at its other end to the cylinder 190 by a hook 240 threaded into an upwardly projecting lug 242 on the cylinder. The tension or resistance of the spring 236 may be varied by means of a nut on the hook 240, and this tension is preferably such that it will be overcome by about fifty pounds fluid pressure per square inch

in the system and in the cylinder 190 before the plunger will start to move to swing the member 230 upwardly about the center 226.

The member 230 has an upwardly facing projection 244 thereon having a somewhat convex top surface. The projection 244 is arranged to underlie a circular end portion 246 of a lever 248, best shown in Fig. 7, and secured to the horizontal arm 70 of the bell crank lever 68 by the shouldered screw 87 which carries the roll 86. The opposite or left-hand end of the lever 248, as viewed in Figs. 6 and 7, is bifurcated and straddles the shaft 72 so that the lever will swing about the shaft with the arm 70.

As indicated above, when the pressure built up in the cylinder 190 overcomes the resistance of the spring 236, the piston 192 moves forwardly or to the left, as viewed in Fig. 9, and, as the pressure in the cylinder increases, the plunger forces the member 230 upwardly about the pivot until the projection 244 engages the portion 246 of the lever 248 thereby swinging this lever and the arm 70 of the bell crank lever 68 (to which it is connected) upwardly or in a counterclockwise direction about the pivot 72. This action of the bell crank lever operates the rocker member 54 to unlock and withdraw the sole and shoe positioning gages from engagement with the sole and shoe and to return them to their outermost or inoperative position illustrated in Fig. 4. The latch 132, which has been permitted by the lowering of the member 180 to ride on the plate 142, drops into latched engagement with the plate when the gages are fully retracted, thereby locking the gages in this position. In order that oil which may leak from the bore of the cylinder 190 through the reciprocative movement of the plunger 192 will not run over the outside of the machine or reduce the amount of oil in the fluid pressure system, the cylinder 190 is provided with a drain pan or lip 252 which is arranged to catch any oil which leaks from the cylinder. A pipe 254 is connected to the portion 252 to carry the oil back into the fluid pressure system of the machine.

Although the operation of the mechanism which forms the subject-matter of the present invention will be apparent from the foregoing description, a summary thereof will be here given for the purpose of clearness.

When a pad box which is to receive a sole and shoe is located at the operating station, the gage arms 18 and 20 carrying the sole and shoe positioning gages are in their outer or retracted position, the gage mechanism being held in this position because the roll 86 is resting on the ledge member 88 which, at this time, is in its elevated position. The gages are free, however, to move inwardly toward the sole and shoe, through the operation of their respective springs, because the swinging frame member 120 is located in its rearwardly inclined inoperative position so that the member or arm 180 is engaging the latch 132 and holding it above the fixed plate 142. The operator places a sole on the pad and depresses the gage treadle 94 to lower the ledge member 88 and permit the sole gages 22, 28 yieldingly to find the edge face of the sole, after which the gages automatically lock. The operator then places the shoe between the locked shoe gages, which position it relatively to the sole, and he swings the swinging frame member 120 forwardly by the handle 124 into its substantially vertical operative position, as shown in Fig. 2, this action turning the shaft 122 and swinging the member 180

downwardly away from the latch 132, thus permitting the latch to descend so that its straight edge portion at the left of the notch in the latch, as viewed in Fig. 6, rides on the upper edge of the plate 142 but the latch does not hook over the plate because the bell crank lever 68 has been swung too far in a clockwise direction, as viewed in that figure, to permit the notch in the latch to engage the plate.

10 The operator then depresses the pressure applying treadle 200 which operates the valve 218 and sends fluid under pressure into the cylinder 110 to elevate the piston 112 and to apply hydraulic pressure to the sole and shoe. As the 15 pressure on the sole and shoe increases the fluid under pressure which is simultaneously entering the cylinder 190 through the pipe 198 is building up the same pressure in the cylinder. Accordingly, if the spring 236 is set to withstand a pressure of fifty pounds per square inch in the system, when this predetermined pressure acting on the piston 112 has been applied to the sole and shoe the spring will yield. As the plunger moves 20 forwardly under the increasing pressure in the cylinder 190, the member 236 will be swung upwardly to elevate the lever 248 and arm 70 and thus rotate the bell crank lever 68 in a counter-clockwise direction about its pivot 72 until the notch on the latch 132 drops over the stationary 25 plate 142, this movement, of course, operating the rocker member 54 to unlock the sole and shoe gage arms and, through the lugs on said rocker member, to force these arms into their outer or retracted positions against their operating 30 springs. Thus it will be seen that the sole and shoe gages are released, withdrawn and latched in inoperative positions automatically by fluid pressure operated mechanism when a predetermined pressure has been applied to the sole and 35 shoe.

The gages remain latched in their inoperative position as the pressure on the sole and shoe increases to the desired amount, so that there is no danger of the gages scarring the shoe as it 40 sinks into the pad. The operator then actuates the turret rotating mechanism and the pad box moves out of the operating station and intermittently around the machine as the other pad boxes are loaded in the manner described, the 45 gages remaining latched in inoperative position all the while. As the pad box under consideration approaches the operating station, the roll 166 rides up on the stationary cam 80 and automatically swings the swinging frame member 120 to its rearwardly inclined position through the 50 operation of the segmental member 146, the pressure on the sole and shoe having, of course, been relieved by other mechanism on the machine before the swinging frame member is swung rearwardly. Rearward movement of the swinging frame 55 120 turns the shaft 122 and actuates the member 180 to elevate the latch 132 and hold it out of engagement with the plate 142. At the same time the roll 86 has moved far enough along the inclined surface 84 of the stationary cam 80 to prevent the released gages from returning under the action of their springs into engagement with the sole and shoe. Accordingly, although the gages are not locked at this time and are free 60 to be moved into operative position by their springs, if permitted, they are nevertheless retained in their outer or retracted positions by reason of the engagement of the roll 86 with the cam 80 and the ledge 88. After the shoe, with 65 its sole attached thereto, has been removed from

the pad the operator places another sole on the pad and repeats the operations described above.

Having thus described the invention, what I claim as new and desire to secure by Letters Patent of the United States is:

1. In a machine for applying pressure to shoe bottoms, the combination of a pad box provided with a pad, means mounted on the pad box for relatively positioning a sole and shoe on the pad, means for pressing the sole and shoe against the pad, and means for withdrawing the positioning means from operative position during the pressing operation.

2. In a machine for applying pressure to shoe bottoms, the combination of a pad box provided with a yieldable pad, means carried by the pad box for relatively positioning a sole and shoe on the pad, means for effecting relative movement between the sole and shoe and the pad to cause pressure to be applied to the sole and shoe, and means for withdrawing the positioning means from operative engagement with the sole and shoe during said relative movement.

3. In a machine for applying pressure to shoe bottoms, the combination of a pad box provided with a yieldable pad, means carried by the pad box for positioning a sole and shoe relatively to each other on the pad, means for pressing the shoe toward the pad to apply pressure to the sole and shoe, and means for automatically moving the positioning means away from engagement with the sole and shoe before the full pressure has been applied thereto.

4. In a machine for applying pressure to shoe bottoms, the combination of a yieldable pad, means for relatively positioning a sole and shoe on the pad, means for pressing the sole and shoe against the pad to apply pressure to said sole and shoe, and fluid-pressure-controlled means for withdrawing the positioning means from engagement with the sole and shoe after the pressing operation has begun.

5. In a machine for applying pressure to shoe bottoms, the combination of a pad box provided with a yieldable pad, gages on the pad box for relatively positioning a sole and shoe on the pad, means for pressing the sole and shoe and the pad together thereby applying pressure to said sole and shoe, and means for withdrawing the gages from engagement with the sole and shoe when a predetermined pressure has been applied thereto.

6. In a machine for applying pressure to shoe bottoms, the combination of a yieldable pad for receiving a sole and shoe, gages movable toward and away from a sole and shoe on the pad for positioning them relatively to each other thereon, means for moving the sole and shoe against the pad while they are held in position by the gages, thereby applying pressure to the sole and shoe, and fluid-pressure-controlled means for withdrawing the gages from engagement with the sole and shoe after the pressure thereon is sufficient to prevent relative displacement of the sole and shoe.

7. In a machine for applying pressure to shoe bottoms, the combination of a pad box, a pad in the box, means carried by the pad box for relatively positioning a sole and shoe on the pad, means for relatively moving the pad and shoe to press the shoe and sole together, and means operated by the application of pressure to the sole and shoe for withdrawing the positioning means from engagement with the sole and shoe and returning them to inoperative position.

8. A machine for cement attaching soles to shoes having, in combination, a pad for receiving a sole and shoe, gages for relatively positioning the sole and shoe on the pad, abutments for pressing the shoe against the pad, thereby pressing the sole and shoe together, hydraulic means for operating said abutments, and means actuated by the operation of said hydraulic means for withdrawing the gages from engagement with the sole and shoe.

9. A machine for cement attaching soles to shoes having, in combination, a pad for receiving a sole and shoe, gages for relatively positioning the sole and shoe on the pad, abutments for pressing the shoe against the pad, thereby pressing the sole and shoe together, hydraulic means for operating said abutments, and means actuated by operation of said hydraulic means for automatically moving the gages into inoperative position during the pressing operation.

10. A machine for cement attaching soles to shoes having, in combination, a pad for receiving a sole and shoe, gages for relatively positioning the sole and shoe on the pad, abutments for pressing the shoe against the pad, thereby pressing the sole and shoe together, hydraulic means for operating said abutments, and means for withdrawing the gages from engagement with the sole and shoe after a predetermined pressure has been applied thereto.

11. A machine for cement attaching soles to shoes having, in combination, a plurality of pads arranged to be presented in turn at an operating station, gages associated with each pad for relatively positioning a sole and shoe thereon when the pad is located at the operating station, means for effecting relative movement of the pad and shoe to apply pressure to the sole and shoe, and means at said operating station actuated by operation of the means for effecting said relative movement for withdrawing the gages associated with said pad before the full pressure is applied to the sole and shoe.

12. A machine for cement attaching soles to shoes having, in combination, a plurality of pads arranged to be presented in turn at an operating station, gages associated with each pad for relatively positioning a sole and shoe thereon, means at the operating station for pressing the shoe against each pad when it is located at said station thereby applying pressure to the sole and shoe, and means at said operating station for automatically withdrawing the gages from each sole and shoe during the operation of said pressure applying means.

13. A machine for cement attaching soles to shoes having, in combination, a plurality of pads arranged to be presented in turn at an operating station, gages for relatively positioning a sole and shoe on each pad, means for pressing the shoe against each pad thereby applying pressure to the sole and shoe, and fluid-pressure-controlled means for withdrawing the gages from operative engagement with each sole and shoe.

14. A machine for cement attaching soles to shoes having, in combination, a pad for receiving a sole and shoe, gages for relatively positioning the sole and shoe on the pad, means for relatively moving the pad and shoe to apply pressure to the shoe and sole, and means controlled by the pressure on the shoe for automatically withdrawing the gages from operative engagement with the sole and shoe before the pressure applying operation is completed.

15. In a machine for applying pressure to shoe

bottoms, the combination of a pad box, a pad in the box, means carried by the pad box for relatively positioning a sole and shoe on the pad, means for locking said positioning means in operative position, means for pressing the shoe toward the pad thereby applying pressure to the sole and shoe, and means for unlocking and withdrawing the positioning means from engagement with the sole and shoe during the application of said pressure.

16. In a machine for applying pressure to shoe bottoms, the combination of a pad box, a pad in the box, means carried by the pad box for relatively positioning a sole and shoe on the pad, means for locking said positioning means in operative position, means for pressing the shoe toward the pad thereby applying pressure to the sole and shoe, and means for automatically unlocking and returning said positioning means to inoperative position after a predetermined pressure has been applied to the sole and shoe.

17. In a machine for applying pressure to shoe bottoms, the combination of a pad box, a pad in the box, means for relatively positioning a sole and shoe on the pad, means for locking said positioning means in operative position, means for pressing the shoe against the pad thereby applying pressure to the sole and shoe, and fluid-pressure-controlled means for withdrawing the positioning means from operative engagement with the sole and shoe before the full pressure has been applied thereto.

18. In a machine for applying pressure to shoe bottoms, the combination of a pad box, means on the pad box for relatively positioning a sole and shoe on the pad, means for pressing the shoe toward the pad thereby applying pressure to the sole and shoe, means for withdrawing the positioning means from operative engagement with the sole and shoe, and means for maintaining said positioning means in a withdrawn position.

19. In a machine for applying pressure to shoe bottoms, the combination of a pad, means for relatively positioning a sole and shoe on the pad, means for pressing the shoe toward the pad thereby applying pressure to the sole and shoe, fluid-pressure-operated means operating during the application of pressure to the sole and shoe for withdrawing the positioning means from engagement therewith, and means for maintaining the positioning means in a withdrawn position until the pressing operation is completed.

20. In a machine for applying pressure to shoe bottoms, the combination of a pad, means for relatively positioning a sole and shoe on the pad, means for pressing the shoe toward the pad thereby applying pressure to the sole and shoe, means for withdrawing the positioning means from the sole and shoe and returning said means to inoperative position before the full pressure is applied to the sole and shoe, and means for latching the positioning means in inoperative position.

21. In a machine for applying pressure to shoe bottoms, the combination of a pad, means for relatively positioning a sole and shoe on the pad, means for pressing the shoe toward the pad thereby applying pressure to the sole and shoe, means for withdrawing the positioning means from engagement with the sole and shoe after a predetermined pressure has been applied thereto, and a latch for maintaining said positioning means withdrawn from the sole and shoe during the rest of the pressing operation.

22. In a machine for applying pressure to shoe

bottoms, the combination of a pad, gages for relatively positioning a sole and shoe on the pad, means for locking the gages in operative position, means for pressing the shoe toward the pad thereby applying pressure to the sole and shoe, means for unlocking and withdrawing the gages from engagement with the sole and shoe before the pressure applying operation is completed, and means for automatically latching the gages in a withdrawn position.

23. In a machine for applying pressure to shoe bottoms, the combination of a pad, gages for relatively positioning a sole and shoe on the pad, means for pressing the shoe against the pad thereby applying pressure to the sole and shoe, means for withdrawing the gages from engagement with the sole and shoe after some pressure has been applied thereto, a latch for maintaining the gages in a withdrawn position, and means for releasing said latch.

24. In a machine for applying pressure to shoe bottoms, the combination of a pad, gages for relatively positioning a sole and shoe on the pad, means for moving the shoe toward the pad thereby sinking the sole and shoe into the pad and applying pressure thereto, fluid-pressure-operated means for withdrawing the gages from engagement with the sole and shoe before they have been sunk any substantial distance into the pad, and means for thereafter maintaining the gages out of contact with the sole and shoe.

25. In a machine for applying pressure to shoe bottoms, the combination of a pad for receiving a sole and shoe, gages for relatively positioning the sole and shoe on the pad, means for locking said gages in operative engagement with the sole and shoe, fluid-pressure-operated means for pressing the shoe against the pad thereby applying pressure to the shoe and sole, means actuated by the operation of said fluid-pressure-operated

means for unlocking the gages and withdrawing them to inoperative position before the full pressure has been applied to the sole and shoe, means for automatically latching the gages in said inoperative position, and means for unlatching the gages after the pressure applying operation is completed.

26. In a machine for applying pressure to shoe bottoms, the combination of a pad for receiving a sole and shoe, gages for relatively positioning the sole and shoe on the pad, means for locking said gages in operative engagement with the sole and shoe, means for pressing the sole and shoe toward the pad thereby applying pressure to said sole and shoe, means for unlocking and withdrawing the gages from the sole and shoe before they have been pressed any substantial distance toward the pad, means for latching said gages in a withdrawn position, means for unlatching the gages after the pressing operation is completed, and means for preventing the gages from contacting again with said sole and shoe after the gages have been unlatched.

27. In a machine for applying pressure to shoe bottoms, the combination of a pad for receiving a sole and shoe, gages for relatively positioning the sole and shoe on the pad, means movable toward and away from the pad for pressing the sole and shoe thereon thereby applying pressure to the sole and shoe, means for withdrawing the gages from engagement with the sole and shoe after pressure sufficient only to clamp the sole and shoe on the pad has been applied thereto, means for latching said gages in a withdrawn position, and means operated by movement of the pressing

means away from the pad for releasing said latching means after the pressure applying operation is completed.

28. In a machine for applying pressure to shoe bottoms, the combination of a pad for receiving a sole and shoe, gages for relatively positioning the sole and shoe on the pad, a member movable into and out of position over the pad for pressing the sole and shoe against said pad thereby applying pressure to the sole and shoe, means for withdrawing the gages from operative engagement with the sole and shoe before the full pressure has been applied thereto, means for automatically latching said gages in an inoperative position after they have been withdrawn, means for causing the pressing member to move away from over the pad after the pressing operation is completed, and means operated by such movement of the pressing member for releasing the latching means.

29. In a machine for applying pressure to shoe bottoms, the combination of a pad for receiving a sole and shoe, gages for relatively positioning the sole and shoe on the pad, a member movable into and out of position over the pad for pressing the sole and shoe against said pad thereby applying pressure to the sole and shoe, means for withdrawing the gages from operative engagement with the sole and shoe when a predetermined pressure has been applied thereto, means for latching said gages in an inoperative position after they have been withdrawn, means for causing the pressing member automatically to move away from over the pad after the pressing operation is completed, means operated by movement of said pressing member into inoperative position for releasing said latching means, and means for preventing the gages from thereafter moving into contact with sole and shoe.

30. In a machine for applying pressure to shoe bottoms, the combination of a plurality of sole receiving pads arranged to be presented in turn at an operating station, gages associated with each pad for relatively positioning a sole and shoe thereon when the pad is located at the operating station, means at the operating station for pressing the sole and shoe against the pad thereby applying pressure to the sole and shoe, means for withdrawing the gages of the pad at said operating station when only a part of the pressure has been applied to the sole and shoe thereon, means for latching the gages in a withdrawn position before the pad leaves the operating station, and means for unlatching the gages before the pad returns to said operating station.

31. In a machine for applying pressure to shoe bottoms, the combination of a plurality of sole receiving pads arranged to be presented in turn at an operating station, gages associated with each pad for relatively positioning a sole and shoe thereon when the pad is located at the operating station, means movable toward and away from the pad at the operating station for pressing the sole and shoe against the pad thereby applying pressure to the sole and shoe, means for withdrawing the gages of the pad at the operating station from the sole and shoe before pressure sufficient to attach the sole to the shoe has been applied, means for latching the gages in a withdrawn position before the pad leaves the operating station, and means operated by movement of the pressing means away from the pad after the pressing operation is completed for unlatching the gages.

32. In a machine for applying pressure to shoe

bottoms, the combination of a plurality of sole receiving pads arranged to be presented in turn at an operating station, gages associated with each pad for relatively positioning a sole and 5 shoe on each pad when it is located at said operating station, means at the operating station for pressing each shoe against its pad thereby applying pressure to the sole and shoe, means for withdrawing the gages from each pad at the operating station after a predetermined pressure 10 has been applied to the sole and shoe thereon, means for automatically latching the gages in a withdrawn position before each pad leaves the operating station, means for unlatching the gages 15 before the pad returns to said operating station, and means for preventing said gages from contacting again with the sole and shoe after the gages have been unlatched.

33. In a machine for applying pressure to shoe bottoms, the combination of a plurality of sole receiving pads arranged to be presented in turn at an operating station, gages associated with each pad for relatively positioning a sole and shoe on each pad when it is located at said operating station, means movable toward and away 20 from each pad at the operating station for pressing the shoe against the pad thereby applying pressure to the sole and shoe, fluid-pressure-operated means for withdrawing the gages from each pad at the operating station after pressure 25 sufficient to clamp the sole and shoe on the pad has been applied thereto, means for automatically latching the gages in a withdrawn position before each pad leaves the operating station, means 30 operated by movement of the pressing means away from each pad for unlatching the gages before the pad returns to the operating station, and means for maintaining said gages in a withdrawn position until they are operated to position another sole and shoe on the pad.

34. In a machine for applying pressure to shoe bottoms, the combination of a plurality of pads for receiving soles and shoes, said pads being arranged to be presented in turn at an operating station, gages associated with each pad for relatively 45 positioning a sole and shoe thereon when the pad is located at the operating station, means including a pivoted lever and springs associated with each pad for operating said gages, treadle operated means at the operating station for actuating the gage operating means, means movable toward and away from each pad at the operating station for pressing the sole and shoe against each pad thereby applying pressure to the sole and shoe, fluid-pressure-operated means for withdrawing the gages from operative engagement 50 with the sole and shoe on said pad after a predetermined pressure has been applied thereto,

means for automatically latching the gages of the pad in a withdrawn position until said pad is again ready to enter the operating station, means operated by movement of the pressing means away from said pad for automatically unlatching the gages after the pressure applying operation is completed, and means at the operating station for preventing the gages from returning to operative position until said treadle operated means is again operated.

35. In a machine for applying pressure to shoe bottoms, the combination of a plurality of sole receiving pads arranged to be presented in turn at an operating station, gages associated with each pad for relatively positioning a sole and shoe thereon, a member at the operating station for pressing the sole and shoe against each pad thereby applying pressure to the sole and shoe, said member being arranged to swing toward and from the pad into and out of operative position, 20 means associated with each pad for operating the gages, means for automatically withdrawing the gages of the pad at the operating station after a predetermined pressure has been applied to the sole and shoe thereon, a latch carried by 25 each gage operating means for maintaining the gages in a withdrawn position until the pressing operation is completed, and means movable toward and from the pad with said pressing member for automatically releasing the latch when 30 the swinging member moves away from position over the pad.

36. In a machine for applying pressure to shoe bottoms, the combination of a plurality of sole receiving pads arranged to be presented in turn at an operating station, gages associated with each pad for relatively positioning a sole and shoe thereon, a member at the operating station for pressing the sole and shoe against each pad thereby applying pressure to the sole and shoe, said member being arranged to swing toward and from the pad into and out of operative position, 35 means associated with each pad for operating the gages, fluid-pressure-controlled means for retracting the gages from the sole and shoe on the pad at the operating station after a predetermined pressure has been applied to the shoe, a latch for holding the gages in their retracted position until the pressure applying operation is completed, and means movable toward and from the pad with said swinging member for holding the latch out of operative position when the swinging member is in its inoperative position, 40 said means permitting said latch to operate only after the swinging member is moved into operative position.

SIDNEY J. FINN.
